Specification for Design.

Patented Jan. 2, 1917.

Application filed October 21, 1916. Serial No. 127,024. Term of patent 14 years.

To all whom it may concern:

Be it known that I, WILLIAM S. HARLEY, a citizen of the United States, residing at Milwaukee, in the county of Milwaukee and State of Wisconsin, have invented a new, original, and ornamental Design for Gear-Wheels, of which the following is a specification, reference being had to the accompanying drawing, forming part thereof.

The figure is a face view of a gear wheel, showing my new design.

I claim:

The ornamental design for a gear wheel, as shown.

In testimony that I claim the foregoing I have hereunto set my hand at Milwaukee, in the county of Milwaukee and State of Wisconsin, in the presence of two witnesses.

WILLIAM S. HARLEY.
